UNITED STATES PATENT OFFICE.

JOHN BLASS, OF GIRARDVILLE, PENNSYLVANIA.

DRILL-BIT.

1,162,211.

Specification of Letters Patent. Patented Nov. 30, 1915.

Application filed December 30, 1914. Serial No. 879,756.

To all whom it may concern:

Be it known that I, JOHN BLASS, a citizen of the United States, residing at Girardville, in the county of Schuylkill and State of Pennsylvania, have invented certain new and useful Improvements in Drill-Bits, of which the following is a specification, reference being had to the accompanying drawings.

10 This invention relates to an improved drill bit and has for its primary object to provide a tool of this character particularly designed for the cutting or drilling of coal whereby the operation is greatly facilitated, 15 and the coal chipped or broken away from the wall in fine particles and pulverizing of the same practically eliminated.

It is a further object of the invention to provide a drill bit which is so constructed that the same will not become wedged in the hole drilled in the mine wall, but may be very easily and quickly removed therefrom.

It is still another object of the invention to provide a drill rod made up of a plurality 25 of sections, and improved means for easily and quickly connecting any number of the sections together or disconnecting the same.

With the above and other objects in view, the invention consists in novel features of 30 construction, combination and arrangement of parts as will be hereinafter referred to and more particularly pointed out in the specification and claims.

Figure 1 is a perspective view illustrating 35 one embodiment of my improved drill; Fig. 2 is a similar view showing a slightly modified form of the drill point. Fig. 3 is a longitudinal section through the joint between the sections of the drill rod; Fig. 4 is a 40 similar view showing a slightly modified form of the joint; and Fig. 5 is a detail perspective view of the end of one of the drill rod sections shown in Fig. 4.

In the ordinary drill now in common use 45 for drilling coal, the end of the drill rod or shank which is provided with the drilling point, terminates in a centrally located chiseling bit, and angularly extending biting bits located upon opposite sides of the chiseling bit disposed in divergent relation thereto. In the use of such a drill, when the drill is inserted into the hole in the mine wall, upon a turning movement of the same in the application of pressure thereto, the central chiseling bit cuts away the

coal and the divergently disposed bits gradually become embedded in the coal wall so that spurs or projections of coal are produced between the longitudinal edges of the chisel and said angularly extending bits. 60 The opposed edges of these cutting bits, grind or pulverize the coal. As the end of the bit is flared or widened, it is obvious that as this cutting progresses, the inner end of the hole in the mine wall is gradually 65 enlarged. Thus considerable difficulty is experienced in withdrawing the drill and the drill points are frequently broken or badly damaged.

My improved coal drilling bit, as illustrated in the accompanying drawing, and more particularly Fig. 1 thereof, includes the chiseling point indicated at 5. The end of the shank 6 of the drill is gradually reduced in thickness or thinned to 75 form this chisel, the extreme end edge of which is sharpened as at 7. It is to be noted that the chiseling bit is gradually flared or increased in width from its inner to its outer end. Upon one side of 80 this chiseling bit, a tapering chipping bit or spur 8 is integrally formed at the inner end thereof. This chipping bit is disposed at an acute angle with relation to the longitudinal axis of the drill shank and tapers to a point, said point being spaced from the end of the cutting edge 7 of the chisel both laterally and inwardly thereof. At the inner end of the chipping bit 8, a second chipping bit 9 is formed, said latter bit also tapering to a point and being disposed at an acute angle with relation to the bit or point 8. The apex or point of the bit 9 is also spaced laterally and inwardly from the point of the bit 8. The distance between 95 these points and between the point of the bit 8 and the adjacent end of the cutting edge 7 of the chisel is approximately three-quarters of an inch, although this space may be greater or less as particular circumstances 100 and requirements may indicate to be necessary. The outer side of the chipping bit or point 9 is inclined inwardly and merges into the side of the drill shank.

In the operation of the drill, it will be 105 obvious that as the two bit projections or points 8 and 9 are both located upon one side of the chiseling bit 5, longitudinal pressure applied in the rotation of the drill will cause the points or spurs of coal entering 110

between the opposed edges of said drill points and chisel to be chipped or broken off. Thus the coal is not ground into a fine powder or pulverized. The side of the drill shank which is opposite to that upon which the bit projections 8 and 9 are formed extends in a straight line in parallel relation to the axis of the shank, to the cutting edge 7 of the chiseling bit. The drill may, therefore, be readily removed from the hole in the mine wall, without the usual binding of the same which necessitates the expenditure of considerable manual labor in order to effect the removal of the drill. The chisel and chipping points are, therefore, relieved of pressure or strain and liability of the same being broken or otherwise damaged is avoided.

In Fig. 2 of the drawing, I have illustrated a slightly different form of my improved drill, wherein the same is provided with a relatively short chiseling bit 10 and the spurs 8' and 9' at one side thereof in a similar manner to the above described form of the device. In addition to these chipping bits or spurs however, I provide the short spur or point 11 on the opposite side of the chiseling bit which extends at an acute angle with respect thereto. The point or apex of this bit 11, is preferably in line with the cutting edge of the chisel. This form of the drilling bit is preferably used when operating upon a course or vein of relatively hard coal, and the additional bit or spur 11 facilitates the entry of the drill point into the face of the mine wall. While I have found in actual practice that the two chipping bits 8 and 9 are sufficient for most purposes, it is nevertheless to be understood that if desired, a greater number of these bits may be provided. The operation and effect of both forms of the drill upon the coal, is substantially the same in the ultimate result, obtained, in that the coal is chipped or broken up in particles, and is not reduced to a pulverized or finely ground condition.

In connection with my improved drill point, I have provided means whereby the length of the drill rod may be readily increased as the hole in the coal wall gradually increases in depth. To this end, the shank 6 is cut away or longitudinally recessed as at 12 on the end opposite the drill point and at the inner end of this recess, the under cut wall or shoulder 13 is formed, said undercut wall being obliquely inclined across the width of the shank. The end face of the reduced portion of the drill shank is similarly beveled or inclined as at 14. The supplementary drill rod section 15 is cut or formed upon one of its ends in a like manner to the shank 6 to mate therewith, and adapted to be disposed upon the same as clearly shown in Figs. 1 and 3 of the drawing. The

reduced portion of the rod section 15 is provided adjacent its end with a point or stud 16 to be received in a circular recess or socket 17 formed in the corresponding portion of the drill shank. The rod section 15 is further provided in its reduced end portion with an opening to receive the split pin 18 which is loosely disposed through an opening provided in the end of the reduced portion of the drill shank 6. It is apparent from this description, that when the reduced portions of the drill shank and the rod section 15 are lapped upon each other and disposed in longitudinal alinement, the end of each section will engage with the under cut 80 wall or shoulder in the other section. The pin 18 is then inserted into the opening of the rod 6 and the mating opening of the rod 15, so that said sections are rigidly held together against longitudinal shifting movement while the pin or stud 16 effectually prevents any relative turning movement of said sections. It is manifest that any desired number of supplementary drill rod sections may be connected together in a like manner. 90

In Fig. 5 of the drawing, I have shown a slightly modified form of this joint connection between the rod sections wherein, instead of using the fastening pin or bolt 18, I provide a locking pin or stud 19 which is fixed to one end of a spring 20. The other end of this plate is riveted or otherwise secured to the drill rod section. In this latter form, it will be understood that the pin 16 on one rod section, engaging in the socket 17 in the other section, is retained. The latter section of the drill rod, in addition to the socket 17, is provided with an opening 21 to receive the spring pressed locking pin 19. This latter form of the joint has the advantage that the locking pin is rigidly secured to the drill rod section and therefore not liable to be lost when the rod sections are disconnected. On the other hand, in some instances, it may be impossible to use this form of the locking device for the rod sections in view of the fact that the metal of the holding spring for the locking pin would be eaten away by the chemical constituents of the mine water. 115 Therefore, in damp mines, the locking bolt or pin 18 would be employed. It will also be understood that this joint connection may be provided for connecting other tools to the rod section such as a scraper or similar implement to scrape out the chipped coal from the hole in the mine wall. 120

From the foregoing description, taken in connection with the accompanying drawing, it is believed that the construction, manner of operation, and several advantages of my improved coal drill will be fully and clearly understood. The invention has been thoroughly tested and found to overcome the deficiencies existing in similar drills at pres- 125

ent in use. Waste of the coal by grinding the same into a fine powder or pulverized form is avoided, and the quantity of coal mined by means of the drill in a predetermined time is greatly in excess of that which is possible in the use of the old forms of such drills. It will also be seen that my improved drill may be as cheaply manufactured as the ordinary coal drill, and owing 5 to the fact that the drill point will not become wedged against the walls of the opening in the coal wall when it is desired to withdraw the same, distortion or other injury to the cutting points of the drill is obviated and expense and delay occasioned 10 thereby eliminated. When however, it is necessary to sharpen the drill points, the shank 6 may be readily disconnected from the rod section, and another drill connected 15 thereto for use while the worn drill bit is being sharpened.

While I have shown and described the preferred form and construction of the several structural features of my improved 20 drill, it will be understood that the same is susceptible of considerable modifications therein and I therefore reserve the privilege of resorting to all such legitimate changes as may be fairly embodied within the spirit 25 and scope of the invention as claimed.

Copies of this patent may be obtained for five cents each, by addressing the "Commissioner of Patents, Washington, D. C."

What I claim is:—

1. A drill of the character described including a shank having a chiseling bit formed on one end and spaced chipping points formed upon one side of the shank 35 and disposed at an angle with respect to each other, the terminals of said chipping points being spaced inwardly from the chiseling bit.

2. A drill of the character described including a shank having a broad, flat chiseling bit formed upon one end, the cutting edge of which is disposed at right angles to the longitudinal axis of the shank, and spaced chipping points obliquely disposed 40 with respect to the axis of the shank, said chipping points projecting from one side of the shank inwardly of the cutting edge of the chiseling bit and the outermost chipping point projecting from the bit shank 45 at the juncture of the other chipping point with said shank, and at an angle with respect to said latter chipping point.

In testimony whereof I hereunto affix my signature in the presence of two witnesses. 50 55

JOHN BLASS.
